CUTICLE STICK

Wilbert J. Gahm, Newark, N.J., assignor to Plura Plastics, Inc., Maplewood, N.J., a corporation of New Jersey

Filed Aug. 12, 1960, Ser. No. 61,725

Term of patent 7 years

(Cl. D86—10)

Fig. 1 is a side elevational view of a cuticle stick embodying my new design,

Fig. 2 is another elevational view thereof rotated 90 degrees; and

Fig. 3 is a cross sectional view taken on the line 3—3 of Fig. 1.

I claim:

The ornamental design for a cuticle stick, as shown.
